UNITED STATES PATENT OFFICE.

HENRY C. LETSINGER, OF NEW YORK, N. Y., ASSIGNOR TO EDWIN C. BURT,
OF SAME PLACE.

IMPROVEMENT IN LADIES' GAITER-SHOES.

Specification forming part of Letters Patent No. **140,836**, dated July 15, 1873; application filed
May 24, 1873.

To all whom it may concern:

Be it known that I, HENRY C. LETSINGER, of the city, county, and State of New York, have invented a new and useful Improvement in Ladies' Gaiters, of which the following is a specification:

Figures 1 and 2 are perspective views of a lady's gaiter made in accordance with my invention. Fig. 3 represents the patterns.

My invention has for its object to improve the construction of ladies' gaiters, so that there will be no seam crossing the instep; and it consists in having the vamp made in one piece with one of the half quarters, and seamed to the other half quarter, the seam commencing at the junction of the overlapping parts, and terminating in the shank between the heel and sole, as will be hereinafter explained.

A represents the vamp of the gaiter made in one piece with the quarter B, as shown in Figs. 1 and 2. The other half quarter C is so formed as to fit upon the vamp A and half quarter B, to which it is sewed to complete the upper of the gaiter. The half quarters being made of two separate pieces they can

be cut so as to give the required shape when sewed together, and thus the usual time, labor, and expense of crimping is saved.

The other parts of the gaiter are constructed in the ordinary manner, and, therefore, need not be here described.

By this construction not only is the inner side of the gaiter made in one piece, and therefore smooth and free from seams, but there is no seam crossing the instep; and hence a common objection to shoes of this kind is obviated.

Having thus described my invention, what I claim therein as new, and desire to secure by Letters Patent, is—

A lady's gaiter having the vamp made in one piece with one half quarter and seamed to the other half quarter, the seam commencing at the junction of the overlapping parts, and terminating in the shank between the heel and sole, as and for the purpose set forth.

HENRY C. LETSINGER.
